UNITED STATES PATENT OFFICE.

WILLIAM ENRIGHT, OF DETROIT, MICHIGAN, ASSIGNOR TO WHITEHEAD & KALES IRON WORKS, OF DETROIT, MICHIGAN, A CORPORATION OF MICHIGAN.

TRACTOR-WHEEL.

1,363,461.

Specification of Letters Patent. Patented Dec. 28, 1920.

Application filed October 31, 1919. Serial No. 334,635.

To all whom it may concern:

Be it known that I, WILLIAM ENRIGHT, a citizen of the United States of America, residing at Detroit, in the county of Wayne and State of Michigan, have invented certain new and useful Improvements in Tractor-Wheels, of which the following is a specification, reference being had therein to the accompanying drawings.

10 The invention relates to wheels more particularly designed for use on tractors and it is among the objects of the invention, first, to obtain a strong, light and inexpensive construction; second, to obtain a standard construction of wheel which is applicable to various specific constructions of hubs; third, to form a cast-in connection between the hub and spokes without danger of weakening the latter. With these and 20 other objects in view the invention comprises the novel construction as hereinafter set forth.

In the drawings:

Figure 1 is a sectional elevation of the 25 wheel;

Fig. 2 is a cross section taken on the plane of the axis of the hub;

Fig. 3 is a cross-section on line 3—3 of Fig. 2.

30 A is the rim of the wheel which may be of any suitable construction, but which as shown is of channel cross-section with the flanges thereof turned radially inward. B is a hub formed of cast metal, and C are 35 wrought metal spokes for uniting the rim and hub.

With certain constructions of wheels heretofore used the spokes have been united to a hub by being cast therein, but it has been 40 found that this method results in the crystallization of the metal in the spoke, frequently causing breaking of the same adjacent to the point of attachment. To avoid this difficulty certain other constructions of 45 wheels have been formed with hubs having radially extending annular flanges to which the spokes are united by riveting. With such constructions, in order to secure the requisite strength in the attachment flanges, the hubs are usually formed of cast steel, this greatly adding to the cost of construction. On the other hand, when the hubs are formed of cast iron, the dimensions are necessarily such as to greatly increase the

weight of the structure. With my improved 55 construction I avoid the objections and difficulties just referred to by forming the hub of cast iron and providing the same with a pressed sheet metal annulus cast thereinto and forming a radially extending flange. 60 This flange forms a means of attachment for the spokes which may be riveted or otherwise secured thereto and the fact that the flange is annular and continuous avoids danger of breaking through weakening by 65 the casting-in process.

In detail, C' is a pressed sheet metal annulus which has an inner portion for embedding in a flange D upon the hub, said portion having a series of apertures E 70 therein for anchoring portions of the casting. The outer portion of the annulus is fashioned for engagement with the spokes and as specifically shown is pressed into a zig-zag form for engagement with spokes 75 extending at different angles. The spokes are preferably formed of straight, flat bars F of wrought metal which at their outer ends are riveted at G to the inwardly-extending flanges A' of the rim. One series of 80 these spokes extends from the rim directly to the flange D of the hub upon the same side of the wheel, while another series extends from the same flange of the rim to the flange of the hub on the opposite side of the 85 wheel. The difference in angle of the two series of spokes is provided for in the zig-zag form of the annulus C' and as indicated at G' are portions in the plane of the spokes F, and G² are portions in the plane of the 90 spokes F', said portions being connected by oblique portions G³. The spokes are preferably placed in the pockets between the oblique portions G² and are secured respectively to the portions G' and G² by riveting. 95

In the complete structure of the wheel there will be a series of spokes on opposite sides thereof extending from the flanges of the hub to the flanges of the rim and also there will be diagonally crossing spokes 100 from the rim flanges on one side to the hub flanges on the opposite side. This produces a very strong trussing of the rim and permits of lightening the structure while still maintaining the requisite strength.

In the manufacture of tractor wheels there are few differences in form of the rim or outer portion of the wheel, but in different

constructions of tractors the hubs of the wheels may be varied. With my construction all the wrought metal parts may be of standard construction and various modified constructions of hub may be used therewith by merely casting in the presed sheet metal member C into the particular hubs required.

Another advantage of my improved construction is the easy replacement of spokes when broken, or otherwise injured. This is by reason of the fact that the spokes are not directly cast into the hub, but are attached to the annulus from which they can be removed and replaced without changing the hub.

What I claim as my invention is:

1. In a tractor wheel, the combination with a rim and a series of spokes extending radially inward therefrom, of a cast metal hub, and a pressed sheet metal annulus cast

into said hub and having an outwardly extending portion for attachment to said spokes

2. A tractor wheel comprising a rim, spokes extending radially inward therefrom, and a pressed sheet metal annulus to which the inner ends of said spokes are attached, all being of standard construction, and hubs of variable design united to the spokes by the casting in of said annulus.

3. A tractor wheel comprising a rim, a cast metal hub, a pressed sheet metal annulus cast into said hub and having its peripheral portion of zig-zag form, and spokes connected to the different angling portions of said zig-zag annulus and extending therefrom to said rim at different points of attachment thereto.

In testimony whereof I affix my signature.

WILLIAM ENRIGHT.
